UNITED STATES PATENT OFFICE.

JOHN W. DOUGHERTY, OF BEAVER, PENNSYLVANIA.

METHOD OF PREVENTING GAS EXPLOSIONS IN BLAST-FURNACES DURING TEMPORARY STOPS.

1,309,466.

Specification of Letters Patent.

Patented July 8, 1919.

Application filed March 20, 1919. Serial No. 283,841.

To all whom it may concern:

Be it known that I, JOHN W. DOUGHERTY, a citizen of the United States of America, and a resident of Beaver, in the county of 5 Beaver and State of Pennsylvania, have invented certain new and useful Improvements in Methods of Preventing Gas Explosions in Blast-Furnaces During Temporary Stops; and I do hereby declare the 10 following to be a full, clear, and exact description of the invention, such as will enable others skilled in the art to which it appertains to make and use the same.

My invention relates to the prevention of 15 explosions in blast furnaces and the auxiliary parts of blast furnace systems during a stop for temporary repairs, and the starting up after a stop for such repairs, and it consists in driving out the gas from the 20 auxiliary parts of the furnace system by means of a non-explosive gas (which, of course, includes steam, nitrogen, carbon-dioxid, or any other inert gaseous medium desired, or convenient to be introduced).

25 This inert medium is for the purpose of driving out the gas from the auxiliary parts and apparatus of the furnace and confining the gas to the furnace without admitting air, and this I do by admitting such medium, preferably steam because it is the 30 cheapest and most convenient, to the dust-catcher, during a stop for repairs, so as to produce an outward pressure in the dust-catcher and its adjacent parts, and at the same time produce a counter pressure at 35 the bottom of the down-comer, so as to confine the gases within the blast furnace itself. I thus produce a few ounces of steam pressure behind the gas in the down-comer that follows up or compensates the loss of 40 volume due to leakage, thereby preventing any air from leaking into the dust-catcher or through any other part adjacent thereto, such as the gas mains, valves, or the like, 45 whereby the explosive mixture could or might be formed.

For example, I drive the gas out of the 50 furnace system or parts of the furnace system by means of the steam. In case of re-pairs, such as the replacement of a bell, steam is admitted to the dust-catcher, or to pipes adjacent thereto to drive gas from the down-comer out from the top of the furnace, and in quantities sufficient to maintain an 55 outward pressure in the dust-catcher.

When the bell is closed for the purpose of replacing a twyer, steam is admitted to the dust-catcher, or to any other part of the system between the boiler and hot blast stoves and the shaft of the furnace, to maintain an outward pressure and to prevent any gas from entering the dust-catcher or other leaky parts of the gas system, the gas being driven out of the pipe lines by means of steam pressure. The air is thus prevented from entering the down-comer and thence into the top of the furnace, by reason of the steam pressure confining the gases within the furnace and preventing the entrance of air at all points of the system 60 on the system.

In replacing a leaking twyer or the twyer cooler, steam pressure is maintained in the dust-catcher, for the reason that 75 when this operation is taking place it is found expedient to connect the tuyers through the bustle pipe and hot blast pipe to the stack by opening a hot blast valve and the draft valve of one of the stoves, 80 the gas valve and cold blast valve having been previously closed. By doing this, the stove stack pulls directly on the interior of the furnace at the tuyers and draws the gas away which would otherwise puff out the 85 opening in the furnace made while a twyer or cooler is being changed. This pull may be sufficient to also draw gas down from the top of the furnace while this drafting operation on the tuyers is taking place. 90

The effect of this at the down-comer and dust-catcher will be the removal of some of the gas from the dust-catcher, and cause some air to be admitted to the catcher or other part of the system if steam is not 95 maintained in the dust-catcher and system sufficient to keep up an outward pressure.

I have heretofore used steam as a plug or insert between a column of gas and a column of air with the steam moving ahead of the 100 gas and following the air in blowing in a blast furnace.

The problem that I have solved in the present instance is to overcome explosions due to an entirely different type of operations, and I have discovered that it may be done with steam, but in this instance the steam is located behind the column of gas, or inserted between two columns of gas in the blast furnace gas system, so as to follow 105 110

up or drive the gas ahead of it and prevent the air from following along and entering the system and thus forming an explosive mixture with the hot gas.

5 The point of introduction of the steam into the gas system may be anywhere between the two ends of the system, that is, any point between the inlet end, or shaft of the furnace, and the outlet end, at the boiler 10 and hot blast stoves.

I have diagrammatically illustrated the invention in the accompanying drawings, in which like parts are similarly designated.

Figure 1 is a diagrammatic elevation of 15 so much part of a blast furnace system as is necessary, showing points of steam introduction.

Fig. 2 is a diagrammatic plan of a blast furnace system, on a smaller scale.

20 The blast furnace is indicated by *a*, the downcomer by *b*, the dust catcher by *c*, the gas main by *d*, the hot blast main by *e*, and the bustle pipe by *f*.

The gas and the hot blast mains *d* and *e* 25 have connected to them various branch pipes, and it is preferable, but not necessary, to make the connections for admitting steam into the gas system between the inlet end of the system where the down-comer *b* leaves 30 the furnace *a* and that point of the gas main *d* where it connects the branch pipes to the other devices.

I have shown the steam pipes *g* and *h* to the down-comer near its beginning at the 35 furnace at 1, and other steam inlets 2, 3 and 4 to points of the gas conduit, as dust catcher and gas main, after leaving the latter.

Any number of such steam inlets may be 40 applied to the gas system between the furnace and the auxiliary apparatus.

In Fig. 2 these connections may be more readily seen with respect to the hot blast stoves, stack and boilers, the boilers furnishing 45 the steam for the plant.

I claim—

1. The method of preventing explosions during a temporary stop in the operation of blast furnace systems, which comprises introducing steam into the gas system at a 50 point between the hot blast stoves and the shaft of the furnace, thereby maintaining a volume of steam between the points of air admission to the system and the gas, the movement of which steam shall be in the direction of movement of the gas.

2. The method of preventing explosions during a temporary stop in the operation of blast furnace systems, which comprises introducing steam into the gas system at a 60 point between the hot blast stoves and boiler burners and the shaft of the furnace, thereby maintaining a volume of steam between the points of air admission to the system and the gas, the movement of which steam 65 shall be in the direction of movement of the gas.

3. The method of preventing gas explosions in blast furnaces during a temporary stop, which comprises maintaining behind 70 a gas volume in the furnace system a volume of steam above atmospheric pressure.

4. The method of preventing gas explosions in blast furnaces during a temporary 75 stop, which comprises maintaining behind a gas volume in the furnace system a volume of inert gas above atmospheric pressure.

5. The method of preventing gas explosions in blast furnaces during a temporary 80 stop, which comprises introducing an inert gas above atmospheric pressure into the system at a point between the points of outflow of gas in opposite directions, and maintaining said pressure while compensating the loss of gas volume in the system during 85 the stop.

6. The method of preventing gas explosions in blast furnaces during a temporary stop, which comprises introducing steam above atmospheric pressure into the system 90 at a point between the points of outflow of gas in opposite directions, and maintaining said pressure while compensating the loss of gas volume in the system during the stop.

7. The method of controlling gas explosions in blast furnaces, which comprises introducing an inert gas under pressure about at the dust catcher of the furnace gas system, and maintaining such pressure during a temporary stop and while drafting the 100 twyers through the hot blast stove stack.

8. The method of controlling gas explosions in blast furnaces, which comprises introducing steam under pressure at about the dust catcher of the furnace gas system, and maintaining such pressure during a temporary stop and while drafting the twyers through the hot blast stove stack.

In testimony that I claim the foregoing as my invention, I have signed my name hereto. 110

JOHN W. DOUGHERTY.
